DES. 2001

Elmer J. Key of Lowell, Massachusetts.

Assessor to

The South Manufactory Company, of the same place.

Letter Patent No. 9001-Dated Nov. 15-1845

Design for a Carpet Pattern

The schedule referred to in these Letters Patent and making part of the same.

It will when it may come

Be it known that E. & E. Lowell, of Lowell,
in the County of Middlesex, and State of Massachusetts, have originated and designed a new pattern for carpets or other fabrics, of which the following is a full, clear and exact description, reference being had to the accompanying drawings, making part of this specification.

A is a centre the particular form of which is shown by the drawing.

B.B.B. Ball has a very good hand and can shape to
the letter X

Centred and cross R.R.B. B rest on the ground. C.C. C.C. pass ground being composed of key work

1. There is an eight pointed figure surrounded by the band F. and resting on a wreath composed of flowers, leaves and branches, said wreath rests on the ground F.

Cisne bianco facciale nesting on the ground. It and surrounded by an irregular border.

The whole design is connected by serpentine scrolls, the interior of which is filled out by flowers and leaves.

2

DES. 2001

The whole design is connected by serpentine scrolls, the interior of which are filled out by flowers and leaves.

The colors employed for the different portions of the design, may be varied to suit the taste and wish of the manufacturer.

Claim.

What I claim as my invention, and desire to secure by Letters Patent is the design or pattern for carpets or other fabrics, herein set forth.
